UNITED STATES PATENT OFFICE

DAVID ADAM CHRISTIAN AND EDMUND WILLIAM PALMER, OF LONDON, ENGLAND,
ASSIGNORS TO SIEMENS BROTHERS & COMPANY, LIMITED, OF LONDON, ENGLAND

TELEPHONE SYSTEM

Application filed June 9, 1930, Serial No. 459,864, and in Great Britain July 1, 1929.

The present invention relates to the control of alternating and/or pulsating currents in electrical circuits.

It is well known that so-called rectifying devices possess the property of offering a low resistance to currents flowing in one direction whilst offering a high resistance to currents flowing in the opposite direction, thereby substantially preventing current flow in that opposite direction.

According to this invention alternating or pulsating current is permitted to flow from a common circuit to a branch circuit or circuits and is prevented from flowing in another branch circuit or circuits by superimposing the alternating or pulsating current on a steady direct current without altering its polarity and connecting rectifiers in the branch circuits to permit the flow of current or not according to the direction of flow of the direct current.

In carrying out this feature each branch may be furnished with a rectifying device and a steady potential is applied to the common part of the circuit. The rectifying devices are so connected that whilst some offer a low resistance to current flow from the common part of the circuit in one direction, others offer a low resistance to current flow in the opposite direction. An alternating or pulsating current superimposed on the continuous current flowing due to the steady applied potential and such that the resultant current is always in the same direction as the continuous current, will then flow in the branch or branches of the divided circuit for which the rectifiers offer a low resistance and will be prevented from flowing in the other branch or branches.

According to another feature of the invention, a telephone system is provided in which stations are connected to two branches of a line and by means of rectifying devices having a steady potential applied to them,

conversations may be held over either branch without interference by the other branch.

In carrying out this feature a rectifying device is connected in each branch and the devices are arranged to permit current flow in opposite directions in the branches. Speech currents are transmitted by modulating a steady current flowing in a circuit and therefore pass in the branch in which the rectifying device offers a low resistance to the steady current but will have no effect on apparatus connected in the other branch. As the variation in the current in the circuit due to speech is small compared with the normal value of the steady current itself, the whole of the speech waves will pass the rectifying device with consequent full reproduction in the telephone receiver.

In a telephone or signalling system the steady potential may be applied at a control point and may provide the current necessary for speech or transmission of signals.

In a further feature of the invention, discriminating arrangements are provided for identifying a branch station at a control point and for the connection of signalling current to the common connecting line for the operation of a particular branch station.

In carrying out this feature, calling signals from the branch stations are transmitted over different wires of the connecting line, and separate call signal receiving apparatus for each branch station is connected to the connecting line at the control point. At a branch station, the calling circuit is preferably completed over a high impedance to a return circuit common to the two branch stations. If manual switching and connecting means are employed at the control point, the connecting line may be joined to separate switching points in opposite directions so that a common connecting link may be employed to connect the source of signalling current in the appropriate direction. Where automatic switching means are used, dis-

crimination may be effected in a similar manner, the signal receiving apparatus operated effecting the connection of signalling current. In the case of calls to a branch station from the control point, the switches which make connection with the connecting line may provide for the correct connection of signalling current. The calling of branch stations from the control point 10 may be effected over different wires as in the case of calls from a branch station.

Reference will now be had to the accompanying drawings which show applications of the invention to party line telephone systems.

In the drawings Fig. 1 shows diagrammatically a two-party line connected to a manually operated telephone exchange, and Fig. 2 shows a similar party line connected 20 to an automatic telephone exchange.

In Fig. 1 the instruments of the two parties are designated X and Y and are shown on the right hand side of the figure connected by a common line *a b* to the exchange. The termination of the line at the exchange is shown 25 on the left hand side of the figure. The line is provided with multiple and answering jacks and line relays for each subscriber and a single cut-off relay is provided for the line, 30 contacts of this latter relay being included in the line relay circuits in the usual manner.

The line relays designated LX and LY for the X and Y parties, respectively, are connected between the negative pole of battery 35 and one of the line wires, relay LX being connected to wire *b* and relay LY to wire *a*. In order that a standard cord may be used a cross is inserted in the connection of the jacks associated with one of the two parties 40 on the line so that the speaking battery is connected to the line with opposite polarities according to the party to be communicated with.

At a subscriber's instrument the receiver, 45 transmitter, induction coil and condenser are connected in the usual manner, but the bell instead of being bridged in series with the condenser across the line wires is connected in series with the condenser between one 50 line wire and earth. The switch hook performs the usual function. At each instrument is a rectifier RX or RY, which is of comparatively low resistance to current flow in one direction and of comparatively high 55 resistance to current flow in the other direction and is connected in one of the line wires at each instrument. The direction of current flow for which the rectifier offers a low resistance is indicated by the arrow head. At 60 the X party's instrument the rectifier is connected in the *a* wire and at the Y party's instrument the rectifier is connected in the *b* wire. A calling key is provided to short circuit the condenser and connect earth over 65 the bell coils to one of the line wires for call-

ing purposes, the line wire being that to which the particular subscriber's line is connected at the exchange. At the X instrument the rectifier is designated RX, the bell CX and the calling key KX, and at the Y 70 instrument these parts are designated RY, CY and KY, respectively.

To make a call subscriber X removes his receiver and presses his key KX thereby connecting earth over the coils of his bell CX, the *b* wire, contact *co1*, relay LX to the earthed battery at the exchange. Relay LX operates and lamp L1 is lit on the closure of contact *lx1* and the operator seeing this plugs into the answering jack JXA. The cut-off relay 80 CO operates over the sleeve circuit and disconnects the two line relays LX and LY at contacts *co1* and *co2* and as the positive pole of battery is connected to the tip of the plug current flows over wire *a* through the rectifier RX and the X party's instrument, the *b* wire, the ring of the plug to the negative pole of the battery. Speech currents being transmitted by modulating a steady current and in this case by modulating current flowing 90 in the circuit and in the direction described, pass through the rectifier and conversation between the operator and the X party can take place. The rectifier RY offers a high 95 resistance to current flowing in the direction described and speech between the exchange and party X cannot, therefore, be heard by party Y. Closure of key KY during the progress of a call between the exchange and party X will not interrupt the call as earth 100 will be connected thereby over the high impedance of bell CY to wire *a* and as the positive pole of the exchange battery is earthed, will not affect the potential applied to rectifier RX.

The subscriber having the instrument designated Y calls the exchange in a similar manner, the calling current flowing over the *a* wire and operating relay LY. To answer this call the operator plugs into the answering jack associated with lamp L2, lit consequent on the operation of relay LY and the positive pole of battery is connected over the tip of the plug and the *b* wire, the jumpers connecting the multiple with the line being 110 crossed, and the rectifier RY presenting only a low resistance to current in this direction, conversation may be had with subscriber Y.

From the above it will be clear without further detailed explanation how a call to either party on the party line may be set up 120 to the exclusion of the other party.

When the operator inserts a plug into a multiple jack, say the jack JY, the current flow over the line is in a direction such that 125 it flows through rectifier RY but not RX. To call the Y party the operator throws her ringing key which applies ringing current between the *a* wire and earth and bell CY is rung. The speech currents being a modula- 130

tion of the steady current pass through rectifier RY and permit conversation with the Y subscriber to be carried on to the exclusion of the X subscriber.

- 5 Referring to Fig. 2, the subscriber's instruments are shown on the left hand side of the drawing and are similar to those shown in Fig. 1 with the exception that dials, represented by contacts D, are provided. The dial 10 is connected in a different line wire at each instrument on the party line. On the right hand side of the drawing is shown a line-switch LS which is used when either of the parties makes a call to search for and take 15 into use a free selector for selecting a route in accordance with a first digit dialled. The final selectors over which access to the party line is had for incoming calls are divided into two groups, selectors in one group having 20 battery feed connections such as to supply current for conversation with one of the parties on the line while the connection of battery in selectors in the other group is reversed so that connection may be had with 25 the other party. Final selectors designated F1 and F2 are shown, there being a cross in the connections to the wipers F2 in order to reverse the direction of battery feed to the called party line.
- 30 The lineswitch is provided with two battery connected line relays LX and LY, connected one to each wire of the party line over contacts of the test relay T. As regards the bank contacts of the lineswitch the connections to these are duplicated, an outlet being connected symmetrically to two sets of contacts in the bank, one in the early part and one in the later part. For instance; if there are ten sets of contacts and five outlets, the 35 first outlet would be connected to contacts 1 and 6, the second to contacts 2 and 7 and so on, there being a normal contact at the commencement of the bank on which the wipers rest when not in use. The connections to the 40 bank contacts are such that current to the calling line from the selector taken into use is fed in opposite directions over the contacts in the two parts of the bank in order that current may flow in the instrument circuit of the calling party only and not in the other instrument, the permission or prevention of current flow in the instrument circuits being determined by the rectifiers RX and RY. In order that a selector shall be 45 taken into use over a route which will feed current in the required direction, the test circuit includes contacts of the two line relays connected to two segments wiped by a wiper of the lineswitch, the segments corresponding to the two sets of symmetrically 50 arranged contacts in the banks giving access to a selector. The switch is rotated by means of magnet DM under the action of an interrupter. Current is fed to the called line over 55 the windings A of the selector impulse relay.
- When a subscriber on the party line makes a call, one of the line relays is operated and the line-switch moves off in search of a free selector, but owing to the separate segments referred to, a selector can only be seized over 60 a route which will feed current in the required direction. Assuming subscriber Y to make a call he lifts his receiver and presses the calling key KY thereby closing a circuit from earth over the coils of his instrument bell CY, dial contacts D, wire a, contact t2 of test relay T, line relay LY to battery. Relay LY operates and at contact ly1 closes a circuit over back contact t1 for magnet DM which operates and rotates the wipers over 65 the bank contacts by means of the interrupter connected in its circuit. The test for a free outlet is battery on the test bank contact and the circuit of the test relay is prepared at contact ly2. When the line switch is stepped from normal, the magnet circuit is earthed over the homing segment and wiper independently of contact ly1. The test circuit cannot be completed if a free outlet is encountered in the early part of the 70 bank as the test relay is disconnected at wiper Z. When however, the wipers are stepped on to the first contacts in the later part of the bank, wiper Z is earthed over the segment corresponding to contacts in the 75 later part of the bank and contact ly2, and when a free outlet is met relay T operates from earth over contact ly2, segment corresponding to contacts in the later part of the bank, wiper Z, the test relay windings, test 80 wiper W, contact in later part of the test bank to battery. Contact t1 changes over, opens the circuit of magnet DM and short circuits the high resistance winding of the test relay to bring the test wiper to substantially earth potential for engaging the outlet. Contacts t2 and t3 disconnect the line 85 relays and switch the line through to the selector S. Dialling tone is given and current is now fed to the line over impulse relay A 90 as follows: earthed positive pole of battery, relay A, contact in later part of bank of wiper B, wiper B, contact t3, wire b, rectifier RY, Y subscriber's instrument, dial contact D, wire a, contact t2, wiper A, contact 95 in later part of bank, relay A to negative pole of battery. The subscriber releases his call key and may now dial the wanted number by means of his dial, producing interruptions in the above traced circuit of relay A which responds to the impulses dialled. When the connection is set up conversation 100 takes place in the normal manner but it cannot be heard by subscriber X as there will be no current flow through his instrument owing 105 to the rectifier RX acting as a high resistance to current flow in the direction above traced. It will be obvious that if subscriber X calls, a similar operation of the lineswitch will be 110 brought about, a selector being taken into 115 the circuit of the selector impulse relay A.
- 120
- 125
- 130

use over the early part of the bank owing to the connection of the test relay T over the first segment and contact l_x2 , and the selector will feed current of polarity positive on wire 5 a and negative on wire b so as to flow through rectifier RX and not through RY. At the end of the call the test relay is released from the selector in the usual manner and at 10 contact $t1$ closes a homing circuit by which the lineswitch is rotated to its normal position where the homing circuit is broken at the homing wiper.

As regards incoming calls, test is made over the final selector test relay (not shown), 15 test wiper and bank contact, normal contact and test wiper of the lineswitch, windings of relay T, normal contact and homing wiper to earth. Relay T operates to prevent rotation of the lineswitch and cuts off the line 20 relays. If the selector F1 is one in the group for calls to X parties positive pole of battery for feeding current to the called subscriber will be connected directly to wire a while in selector F2 of the group used for Y party 25 calls positive pole of battery is connected over the cross in the connections to the final selector wipers to wire b . The subscriber's bell is rung by the connection of ringing current at the final selector between a line 30 wire and earth. The battery feed and ringing connections in the final selectors are the same in the two groups of final selectors, the ringing current being applied to the appropriate wire by the direct or crossed connection 35 to the final selector wipers.

What is claimed is:

1. In a telephone system, two stations connected to a common line, means for establishing a talking connection with the subscriber 40 at one of said stations, and means comprising a rectifier at the second station for preventing the subscriber thereat from interfering with said talking connection.
2. In a telephone system, a central office, 45 two stations, a common line interconnecting said central office and said stations, means for applying battery to said common line at said central office, and means dependent on the polarity of said battery for establishing 50 a talking path between said central office and one of said stations to the exclusion of the other.
3. In a telephone system, a central office, 55 a common line, two stations connected to said common line, answering and multiple jacks at said central office for each of said stations, means at said stations for signalling the operator at said central office, means for establishing a talking connection between the 60 operator at said central office and one of said stations, and a rectifier for preventing the other of said stations from listening in on said talking connection.
4. In a telephone system, a central office, 65 two stations, a common line interconnecting

said stations with said central office, means at said central office for connecting a steady potential to said common line, and means at said stations for permitting one of said stations but not the other to use the line, the 70 station to use the line being determined by the polarity of said steady potential.

5. The method of allowing entry of alternating or pulsating current from a common circuit into a branch circuit or circuits and barring entry into another branch circuit or circuits, which consists in applying a steady direct current to the common circuit, in superimposing the alternating or pulsating current thereon, and in barring or permitting 80 the entry of the resultant current into the branch circuit or circuits dependent on the direction of flow of the direct current.

6. In a telephone system, a central office, 85 two stations, a common two-wire line interconnecting said central office and said stations, means at the central office for transmitting a calling signal over said line in a circuit including one wire of said line and ground, a different line wire being used for 90 signalling each of said stations, means at the central office for applying potential to said line, and rectifiers connected at each of said stations for permitting the subscriber at either of said stations to respond to said 95 calling signal to the exclusion of the other dependent on the polarity of said potential:

7. In a telephone system, two stations, a central office, a common two-wire line interconnecting said central office and said stations, a set of jacks for each of said stations terminating said common line at said central office, the termination of said common line at one of said sets of jacks being reversed as regards said line wires, means at 100 said central office for applying current to said line in either direction dependent on the jack used, and rectifiers connected in opposite sides of said line at said stations to permit either of said stations to use the line to the 105 exclusion of the other dependent on the direction of current flow in said line.

8. In an automatic telephone exchange, a line switch having two line relays, a trunk leading to a selector, said line switch having access to said trunk in two sections of its bank, the trunk being reversed in one of said sections, two stations connected to a common line terminating in said line switch, means 110 responsive to the initiation of a call at either one of said stations for operating the corresponding one of said line relays, the line relay operated determining over which section of said bank said line switch will search for said trunk, and means at each of said stations for preventing a subscriber at the other station from listening in on said call.

9. In a party line lock-out system, two stations connected to a common two-wire line, 115 the line wires terminating one of said sta-

- tions being reversed as regards the line wires terminating in said other station, a rectifier connected in one of said line wires at one of said stations, a rectifier connected in the 5 other of said line wires at said other station, a central office, means responsive to the initiation of a call by either one of said stations for connecting a positive potential to one of said line wires, the station initiating the call de-
 10 terminating the line wire the positive potential will be connected to, said rectifiers permitting one of said stations and preventing the other of said stations from using said line dependent on the side of said line said positive potential is connected to. 80
10. In a telephone system, a partly line, two stations on said line, a common battery transmitter at each station adapted to be supplied with talking current over said party 20 line from the exchange, means at one station effective to prevent current flowing over the line in one direction from passing through the associated transmitter, and means at the other station for preventing current flowing 25 over the line in the other direction from passing through the associated transmitter. 85
11. In a telephone system, a party line, two stations on said line, a transmitter at each station adapted to be bridged across the line, 30 a rectifier in series with one transmitter to bar current flow from the line in a particular direction, and a rectifier in series with the other transmitter to bar current flow from the line in the opposite direction. 90
12. A telephone system as claimed in claim 11 in which two answering jacks are provided for the party line at the exchange, and a reversal in the line branch connected to one jack whereby transmitter current will be 35 connected to the line in one direction on answering a call from one station and in the other direction on answering a call from the other station. 100
13. In a telephone system as claimed in claim 11, a line switch for extending the line responsive to a call from either station, and means responsive to a call for automatically connecting transmitter current to the line in one direction if one station is calling and in 40 the other direction if the other station is calling. 105
14. In a telephone system, a party line, two stations on said line, a switch having two bank sections over which calls from said two 45 stations are extended, respectively, means at each of said stations for starting the operation of said switch to extend a call, and means in said switch controlled by the station initiating a call for determining the bank section 50 over which the call is to be extended. 110
15. In a telephone system, a party line, two stations on said line, a switch having two line relays, one for each station, two bank sections for said switch over which calls from said 55 two stations are extended, respectively, means 115
